UNITED STATES PATENT OFFICE.

LESLIE R. N. CARVALHO, OF TOLEDO, OHIO, ASSIGNOR TO THE CLOSURE SERVICE COMPANY, OF TOLEDO, OHIO, A CORPORATION OF OHIO.

RECEPTACLE CLOSURE.

Application filed July 5, 1923. Serial No. 649,577.

My invention relates to a receptacle closure or cap adapted for use with bottles, jars or other containers. More particularly, it relates to a type of closure comprising a detachable portion which serves to secure the closure in sealing position. In order to remove the cap from the container the first time, said detachable portion is torn off and discarded, after which the cap may be used 10 as a temporary closure.

As herein shown, the cap comprises a cover portion and a flange portion. The flange is scored adjacent its lower edge to form a detachable attaching strip which serves as a 15 means for securing the cap to the container.

In my co-pending application, Serial Number 511,392, filed October 29, 1921, I have shown a closure with an attaching strip of the character above indicated, having one 20 end extended to form a tongue or finger-piece which may be grasped for ripping off the attaching strip.

An object of the present invention is to provide an improved form of attaching strip 25 in which the finger-piece extension is omitted, thereby avoiding the objections incident to a finger-piece projecting beyond or overlying the body of the cap, and also resulting in a substantial saving in the sheet metal 30 from which the cap is formed. The attaching strip is preferably formed with a bead or hollow rib extending lengthwise thereof, and provides a means for engagement of a tool for ripping off the attaching strip.

Other objects of the invention will appear 35 hereinafter.

In the accompanying drawings:

Figure 1 is a part sectional elevation of a 40 container and closure cap, constructed in accordance with my invention.

Figure 2 is a section at the line II—II on Figure 1.

Figure 3 is a view showing the method 45 of using a tool for ripping off the attaching strip.

The closure or cap comprises a cover piece 5 and a flange portion or skirt 6 attached thereto by means of a bead 7. The container to which the cap is applied is here shown as 50 a bottle 8, having a neck provided with a shoulder 9. The lower edge 10 of the cap is bent inwardly beneath the shoulder 9 to hold the cap in sealing position. A gasket 11 may be used to form a tight seal.

55 The flange portion 6 of the cap may be

made of a strip of sheet metal bent to cylindrical form and having its edges overlapped and connected by a seam 13. A removable strip 14 at the lower edge of the flange 6 is provided by scoring the flange 60 along a line 15 extending circumferentially of the cap. The attaching strip 14 is formed with a hollow rib or bead 16 extending lengthwise thereof. Although this bead is herein shown as extending the entire length 65 of the removable strip, it may, if desired, be much shorter. The bead provides a space between the cap and the neck of the bottle, permitting any pointed tool, as for example, the tine of a fork 17, to be inserted for tearing off said strip.

As shown in Figure 1, the flange portion 6 is cut away at the lower end of the seam 13 to provide a space 18 between the ends of the strip 14. This facilitates the use of the 75 tool 17. If desired, the strip 14 may also be cut away at an additional point or points 19 (Fig. 2). Formation of the two open points permits removal of a portion of the strip at a time and consequent elimination or 80 difficulties experienced where a part of the strip tears away before it has performed its function.

When it is desired to remove the cap from the container, the fork tine, or other implement, is inserted beneath the bead 16 at the opening 18 (or 19) and the strip 14 ripped off by a movement of the tool lengthwise of said strip. After the tearing off of the strip has been started by the tool, the end 20 may, 85 if desired, be grasped by the fingers and the strip readily removed.

Modifications may be resorted to within 90 the spirit and scope of my invention.

What I claim is:

1. A closure comprising a cover portion and a skirt or flange, said flange being circumferentially scored adjacent its lower edge to provide a removable strip comprising that portion of the flange between the score and 100 bottom edge of the flange, said strip being formed with a hollow bead extending lengthwise thereof and shaped to permit the insertion of a tool between the strip and the container to which the closure is applied. 105

2. A closure comprising a cover portion and a skirt or flange, said flange being circumferentially scored adjacent its lower edge to provide a removable strip comprising that portion of the flange between the score and 110

bottom edge of the flange, said strip being shaped to permit the insertion of a tool between said strip and the container to which the cap is applied.

5. 3. A closure comprising a cover portion and a skirt or flange, said flange being circumferentially scored to provide a removable strip comprising that portion of the flange between the score and bottom edge of the flange, said strip comprising a hollow convex projection or bead extending lengthwise thereof and presenting an end opening for the insertion of a tool between the bead and the container to which the closure is applied.
10. 4. A closure comprising, in combination, a cover portion and a flange portion connected thereto by a seam, said flange portion comprising a sheet metal strip bent to cylindrical form and having its ends connected by a seam, said flange portion being scored circumferentially adjacent its lower edge to provide a removable attaching strip, said strip being cut away at one point in its periphery to permit insertion of a tool between said strip and the container to which the cap is applied.

15. 5. A closure comprising, in combination, a cover portion and a flange portion connected thereto by a seam, said flange portion comprising a sheet metal strip bent to cylindrical form and having its ends connected by a seam, said flange portion being scored circumferentially adjacent its lower edge to provide a removable attaching strip, the flange portion being cut away at the lower end of said vertical seam to provide a space between the ends of said removable strip, the latter being formed to permit a tool to be inserted between an end of the strip and 20 the container to which the closure is applied.

25. 6. A closure comprising, in combination, a cover portion and a flange portion connected thereto by a seam, said flange portion comprising a sheet metal strip bent to cylindrical form and having its ends connected by a seam, said flange portion being scored circumferentially adjacent its lower edge to provide a removable attaching strip, said removable strip being formed with an 30 outwardly projecting bead, concave on its inner side and having the concavity exposed at one end of the removable strip when the closure is in position on a container, to provide a space for the insertion of a tool.

35. 7. The combination of a container having a neck portion provided with a shoulder, a closure or cap comprising a flange portion having its lower edge bent inward beneath said shoulder for attaching the cap to the container, said cap being circumferentially scored above said edge to form a removable strip, said strip being formed with a hollow rib immediately above the shoulder providing an annular space between the container and said strip, the latter being cut away at

one point in its periphery to provide for the insertion of a tool between said strip and the container.

8. A closure for a container comprising a circular cover portion and a depending flange portion, the latter formed with a hollow outwardly convexed rib extending circumferentially thereof adjacent its lower edge, said flange portion being cut away at one point to expose an open end of said rib, and means permitting separation of the rib from the flange and container.

9. The combination of a container and a sheet metal closure therefor, the latter formed with a hollow rib extending transversely of the container and providing a space between the wall of the container and the rib, the latter being open at its end to permit the insertion of a tool, said closure having a score line entirely above the rib and terminating in said open end permitting removal of the rib from the closure and container.

10. The combination of a container and a closure therefor, the latter comprising a circular cover portion and a cylindrical flange portion depending therefrom, said flange portion comprising a hollow rib extending circumferentially thereof and providing a space between the rib and the adjacent wall of the container, said rib being cut away at one point in its length to give access to said space.

11. The combination of a container having a neck portion provided with an annular shoulder, a closure comprising a flange portion having its lower edge turned inwardly beneath the shoulder for attaching the closure to the container, said flange being formed with a hollow rib extending circumferentially of the flange at a point immediately above said shoulder to provide an annular space between the container and rib, said flange having a circumferential score line immediately and entirely above said rib, and means permitting insertion of a tool in said annular space to separate the bead from the container and closure along said score line.

12. A closure for a container comprising a circular cover portion and a depending flange, said flange having a circumferential score line immediately above the lower edge to provide a tearing strip removably united to the body of the flange, and means extending transversely of the strip at circumferentially spaced points, dividing the strip in distinct portions and permitting removal of one portion of the strip independently of the remaining portion, each said portion being united to the body of the flange along a portion of the score line.

13. A closure for a container comprising a circular cover portion and a depending flange portion, said flange portion being circumferentially scored immediately above the

lower edge to provide a removable strip, means permitting independent removal of one portion of the strip, and additional means limiting the length of the first portion removed and allowing removal of the remaining portion.

14. A closure for a container comprising a circular cover portion, a separate independently removable skirt portion comprising a sheet metal strip bent to cylindrical form and having its ends connected by a seam, said skirt scored circumferentially near its lower end to form a tearing strip, means extending transversely of the strip and merging into the seam to permit tearing away a portion of the strip, and means spaced circumferentially from the other means and extending transversely of the strip to limit the length of the portion first torn away and allow application of means for removing the remaining portion.

15. A closure for a container comprising a circular cover portion and a separate skirt portion united thereto and consisting of a sheet metal piece bent to cylindrical form and having its ends united by a seam, said skirt being scored circumferentially near its lower edge to form a tearing strip having ends adjacent said seam, means dividing said tearing strip into distinct parts, said means extending transversely of the strip to permit one of said parts to be entirely removed from the skirt independently of the other part by tearing along said score, each of said parts being directly connected to the skirt along a portion of the score line independently of the other part.

Signed at Toledo, in the county of Lucas and State of Ohio, this 30th day of June, 1923.

LESLIE R. N. CARVALHO.
